UNITED STATES PATENT OFFICE.

SAMUEL E. BALL, OF DAYTON, OHIO, ASSIGNOR TO AMOS B. HOSTETTER, OF LANCASTER, PENNSYLVANIA.

CIGAR-TIP CUTTER AND MATCH BOX AND LIGHTER.

SPECIFICATION forming part of Letters Patent No. 591,523, dated October 12, 1897.

Application filed February 16, 1897. Serial No. 623,681. (No model.)

To all whom it may concern:

Be it known that I, SAMUEL E. BALL, a citizen of the United States, residing at Dayton, in the county of Montgomery and State of Ohio, have invented certain new and useful Improvements in a Cigar-Tip Cutter and Match Box and Lighter; and I do hereby declare the following to be a full, clear, and exact description of the invention, such as will enable others skilled in the art to which it appertains to make and use the same.

This invention relates to improvements in a device comprising a cigar-tip cutter and match box and lighter of that class in which a reciprocating lever, carrying a cutter-blade, moves a sliding plate or plunger upwardly and downwardly through the body of a match-receptacle and through the top thereof, bringing up a match on its upper edge in each upward movement and holding it against the under face of an arm or strip, (said match on being withdrawn therefrom will be ignited,) in which a spring is adapted to hold said lever normally in upward position, and in which provision is made to prevent the matches from crossing or tangling, arranging them straight or parallel in the bottom of the match-box for the plunger to take them up one at a time.

The object of the invention is the production of a device to expeditiously cut off the tip-end of a cigar preparatory to smoking, to gather or assemble the cut-off tips, and to bring from a receptacle a single match, which, in being taken from the device, will be ignited and ready for lighting the cigar, the whole constituting a convenient smoker's companion.

The elements of the invention will severally and at large appear in the following description, and will be separately and collectively set forth in the claims.

The purposes of the invention are attained by the mechanism illustrated in the accompanying drawings, similar reference letters and figures designating like parts throughout the several views, in which—

Figure 1 is a front elevation of a device embodying the elements of the invention. Figs. 2, 3, and 4 are sections through the casing, taken, respectively, on the lines $x-x$, $y-y$, $z-z$ in Fig. 1; and Fig. 5 is a view from the right

of a portion of Fig. 2 completed, the upper part appearing in section, taken on the line $u-u$.

In the drawings, A designates a suitable supporting framework or casing mounted on legs or feet a , through which nails or screws 5 may serve to secure it in position on a table, bar, or counter. At one end thereof, preferably the left-hand one, is a housing-chamber A' , having on its bottom and movable in and out through an end wall a drawer a' to receive the cigar tips or ends as they drop from the cutter, while on top, at the other or right-hand end of the framework, is a hopper or match-receptacle A^2 , adapted to receive and hold the matches to be used and having its upper end or mouth closed by a trap or door a^2 , hinged along one edge thereof, as at 2, and which door may be locked when so desired (not shown in the drawings) and opened 60 when matches have to be placed thereinto. The bottom of the hopper inclines or slopes downward from front and rear, forming a valley or longitudinal depression along the top of the right-hand extension of the framework, 75 and in which is situated an opening prolonged downwardly through the body of said extension to constitute a guide or passage way a^3 for a plunger-plate A^3 to move up and down therein, carrying a match 3 with it in each upward movement, and the upper edge of the plunger is provided with a shallow concaved groove a^4 to securely hold said match. In the rearward side wall of the extension is a vertically-disposed slot a^5 , through which a connection or pivot-pin, yet to be described, 80 serves to convey to said plunger the required motion, while at a prescribed point in the forward side wall and opening into the chamber A' , before mentioned, is an inwardly-90 rounded or countersunk aperture a^6 , in which the cigar ends are inserted for the cutter, yet to be described, to cut off their tips.

In the rearward portion of the bottom of the hopper is provided with vertically-disposed 95 slots a^7 , through which move agitator-pins a^8 to arrange the matches, laying them straight to enter the groove in the plunger-top when it reaches the lowest point in the hopper-bottom, while underneath said bottom are arranged guide-slots a^9 , in which move the ends of a bar A^4 , from which said pins a^8 project,

and within the hopper is arranged a tumbler blade or wing A⁵, having central side gudgeons journaled into the hopper sides. One gudgeon, preferably the left-hand one, extending outwardly beyond the adjacent wall, is provided with a crank-arm a¹⁰ to reciprocally rotate or shake said blade, helping to lay said matches straight, preventing their crowding at the lowest point, while in the top of the lower portion of the hopper is a slot or opening a¹¹, having sufficient extent and through which the plunger passes in carrying the match on its upper end to the igniting-strip, yet to be described.

15 To the left of the hopper and projecting upwardly from the top of the casing is a column or post a¹², supporting on its upper end a horizontally-placed strip or arm A⁶, extending to the right and having one end securely affixed to said post by a screw or rivet 4, while underneath the strip and secured thereto in any approved manner is a strap-spring A⁷, having a roughened under face against which the plunger, before mentioned, brings the required match and which ignites said match when it is withdrawn therefrom.

Underneath the hopper and lying close to the rearward face of the front wall of the framework is arranged an arm or lever B with its left-hand portion within the chamber A', before mentioned, and its extremity pivoted to the framework by a stud and pin 5. At a point opposite the orifice a⁶, before mentioned, in the forward face of the lever-arm is a dove-tailed recess b, into which is fitted a cutter-blade B', provided with a vertical slot b', through which a screw B², with an eyed washer b² and nut on its rearward end, serves to adjustably secure said cutter-blade in place, while a coiled spring B³, having one end secured through the eye of said washer and the other end b³ secured through an eye depending from the under face of the top wall of the casing, serves to hold said lever normally up, and the right-hand end of the lever is upwardly turned and the extremity thereof finished with a knob or button b⁴, on which a downward hand-pressure serves to depress said lever, the spring returning it again to the upward position. To the left of the hopper a partially-coiled link B⁴ connects the lever with the outer end of the crank-arm a¹⁰, before mentioned, giving to the blade A⁵, also before mentioned, the required reciprocating motion, and below the hopper a coiled spring B⁵ connects the lever with the agitator-bar A⁴, likewise before mentioned, giving to the latter the required motion, but in order that the pins a⁸ of said bar may be held in upright

position the upper end of said link must be 60 rigidly secured into the body of the bar or soldered thereto, while a link B⁶ has its upper end pivoted to the forward face or side of the lever by a bolt and nut b⁵ and its lower end, through the slot a⁵, as shown, pivoted to the 65 plunger-plate A³, before mentioned, whereby the latter is raised or lowered as the lever is elevated or depressed.

It will here be observed that instead of the bar A⁴ moving the pins a⁸ through the slots 70 a⁷ and the tumbler blade or wing A⁵, here shown and described, bars or flat pieces may be arranged to have their upper ends made to move up and down through said slots to agitate or arrange the matches in the hopper, 75 and the chamber A' may have its walls extended underneath the hopper to the right-hand end of the framework without departing from the spirit of the invention or introducing any new features, all of which appear 80 to be so evident that it is deemed superfluous to give them separate illustration.

Having now described the invention and ascertained the manner in which it is performed, what is considered new, and desired 85 to be secured by Letters Patent, is—

A cigar-tip cutter, match-box, and lighter, comprising a casing or framework having a vertical side wall with an aperture through its body and a hopper or match-box on its 90 top at one end thereof, a lever lying adjacent thereto with one end extending beyond the hopper and the other end pivoted to said side wall near the other end thereof, a cutter-blade secured to said lever and adapted to 95 move over the adjacent opening of said aperture, a spring having one end secured to the lever and the other end to the casing, a plunger-plate in guideways within said side wall and movable up and down through the 100 body of said hopper and through a slot in the top thereof with pivoted link connections between the adjacent sides of said plate and said lever, a match-igniting strip secured to the adjacent side of an arm extended over 105 the slot in the hopper-top and having one end secured to a projection from said casing, with means provided to agitate or shake the matches within the hopper or match-box, all substantially as described and for the purpose hereinbefore set forth.

In testimony whereof I affix my signature in presence of two witnesses.

SAMUEL E. BALL.
